[57] CLAIM

The ornamental design for a case for electronic clinical thermometer, substantially as shown and described.

DESCRIPTION

FIG. 1 is a perspective view of a case for electronic clinical thermometer showing our new design;
FIG. 2 is an another perspective view thereof showing opened state;
FIG. 3 is a front view thereof;
FIG. 4 is a rear view thereof;
FIG. 5 is a left side view thereof;
FIG. 6 is a top plan view thereof;
FIG. 7 is a bottom plan view thereof; and
FIG. 8 is a sectional view thereof taken along the line 8—8 in FIG. 3.

FIG. 2

FIG. 1

FIG. 3

FIG. 4

FIG. 5

FIG. 6

FIG. 7

FIG. 8
